UNITED STATES PATENT OFFICE.

JOHN SHEARMAN DONALDSON, OF NEW YORK, N. Y.

DRESSING TOOL.

Application filed November 21, 1924. Serial No. 751,233.

This invention relates to dressing tools of the kind used for dressing and truing abrasive wheels having a rotatably mounted dressing wheel carried at one end of a shank 5 the other end of which is provided with or formed to serve as a handle when the tool is to be used as a hand tool. The dressing wheels used in such hand dressing tools are commonly made with V-notched or multi-pointed peripheries and become more or less rapidly worn down in use and have to be renewed from time to time. It is necessary, therefore, that the tools be made so as to permit of removal of worn wheels and substitution of new wheels. In the tools heretofore used, this replacement of the dressing wheels has been a bothersome operation, taking considerable time, and to provide for such renewal the tools have been made with 10 laterally projecting parts which interfere with the use of the tool in cutting close in to corners on the abrasive wheel which is being shaped. Difficulty in the use of such tools heretofore has resulted, also, from the wearing away of the axle pins of the dressing wheels and of the bearings for such pins, resulting in the dressing wheels getting out of true in a comparatively short period of use.

30 The present invention aims generally to provide an improved hand dressing tool. More particularly, the invention aims to provide a tool in which the dressing wheels after becoming worn may be removed and new ones set in place with comparative ease and speed and without requiring the use of a wrench or other tool; to avoid lateral projections on the tool and thus to enable the tool to be used closer in corners of the work; 35 and to provide a mounting for the dressing wheel such that the wheel shall always run true on a true bearing and without the friction which results from worn and uneven bearings. Other objects and advantages of 40 the invention will appear from the following description of a tool of approved construction embodying the features of the invention as illustrated in the accompanying drawings. In said drawings:

50 Fig. 1 is a side view of the tool;

Fig. 2 is a top plan view of the head end of the tool;

55 Fig. 3 is a side view of the head end of the tool showing the side plates and dressing wheel slid forward to the position in which the side plates are applied to or re-

60 moved from the end of the shank, the cover of the side plate which is seen being removed and the bolt for holding the side plates and the rivets for holding the cover 60 plate being shown in section;

Fig. 4 is a sectional view taken on line 4-4 of Fig. 1;

Fig. 5 is a sectional view on line 5-5 of Fig. 1.

65 Referring to the drawings, the tool comprises a shank 10 formed as a handle 11 at one end and carrying at its other, or head, end two removable side plates 12 and 13, the ends of which extend beyond the ends of the shank and have mounted between them the dressing wheel 14. The head end of the shank is formed on opposite sides with flat bearing faces 15 against which the side, or carrier, plates 12 and 13 are seated. The 70 side plates are held by a bolt 16 which extends through an opening near the end of the shank and through longitudinal slots 17 in the side plates and has on each end a flat permanent head 18 which extends over 75 the edges of the slot to hold the plate. Means are provided for preventing the side plates from turning on the bolt 16 while held against the bearing faces of the shank. Most desirably for this purpose the shank 80 is formed on each side with laterally extending upper and lower portions or flanges 20 and 21 which provide shoulders along the edges of the bearing faces 15, and the side plates are made of a width to fit between 85 these shoulders. The plates are thus held against turning, but unless otherwise held may be moved longitudinally as permitted by the slots 17. The inner ends of the slots 90 17 are enlarged to permit the side plates to 95 be removed from the shank when they have been moved forward from their normal position to the position shown in Fig. 3, the enlargement at the end of the slot being of sufficient size to permit the bolt heads to 100 pass.

105 The ends of the bolt 16 serve as headed studs for holding the side plates to the shank head, but a removable bolt is used for convenience, and to permit the permanently headed bolt to be placed in the bolt opening in the shank, the bolt opening is made, as shown in Fig. 3, open at the top. For holding the side plates in normal or operative position, as shown in Figs. 1, 2 and 4, a 110 spring-held stop piece or latch 22 is provided carried by a flat spring 23 and posi-

tioned to enter notches 24 in the edges of the side plates when the plates are in normal position. For hand tools, the stop piece and notches are formed to prevent movement of the side plates in either longitudinal direction. For convenience in placing and removing the bolt 16 the outer wall of the bolt opening is cut away as shown in Fig. 3 from a point sufficiently above the position of the bolt.

The outer end of each side plate carries an anti-friction bearing 25 for one end of the axle pin 26 on which the dressing wheel is mounted. These bearings are best made to be bodily removable, having as shown an outer race which fits in a recess 27 extending inward from the outer side of the side plate and an inner race which has a central opening to receive the end of the axle pin. The axle pin 26 has a central portion 28 and reduced end portions. A bushing 29 is desirably mounted on the central portion 28 of the axle pin, and the dressing wheel is mounted on the bushing, the wheel, the bushing and the axle pin being free to turn relatively to each other. The bushing 29 and the enlarged central portion 28 of the axle pin desirably extend into the openings in the side plates. A thin removable cover plate 30 is secured on each side plate. The cover plates are formed with slots coinciding with the slots 17 of the side plates so that it is not necessary to remove the cover plates in removing and replacing the side plates. The cover plates need to be removed only to permit removal of the anti-friction bearings and they are therefore most desirably secured by small rivets 31 rather than by screws. So held, the cover plates may be readily removed by cutting off the heads of the rivets and readily re-riveted in place again. If the plates were held by screws there would be danger of the screws becoming loosened by the vibration incident to the use of the tool.

Any suitable dressing wheels may be used. Usually what are known as Huntington dressers are used, these being thin disks of very hard tempered steel and peripherally notched to form a multiplicity of V-shaped teeth. Two or more of these disks are usually placed flatwise together separated by washers of hard tempered steel of a size to extend out to the points of the disk teeth. The drawings show a thin dressing wheel made up of two disks separated by a washer. For wider, or thicker, wheels the flat-sided head end of the tool shank 10 is made thicker and a longer axle pin 26, a longer bushing 29 and a longer holding bolt 16 are used. For wheels of differing thickness, therefore, the same side plates with their anti-friction bearings may be used with a shank having its flat-sided head end of the proper thickness to suitably space the side plates to re-

ceive the wheel, and with a holding bolt, axle pin and bushing of the proper corresponding length.

It is desirable to make the side plates so that they may be endwise reversible, that is, so that they may be secured to the shank with either end extending outward beyond the end of the shank. For this purpose each side plate is made, as shown, with each end the duplicate of the other, having a similarly placed opening for the axle pin and bushing and similarly recessed from its outer side for receiving the anti-friction bearing, and the bolt slot 17 of each plate being located midway between the ends of the plates and having an enlargement for passing the bolt head at each end thereof. Also there is a notch 24 for the stop piece 22 in each of the opposite side edges of each plate. When such endwise reversible side plates are provided, if one end of a side plate becomes worn off or otherwise damaged in use, the plate may be removed, the roller bearing taken out and set in the other end of the plate, and the plate replaced with its undamaged end outward. The side plates are also duplicates of each other, the plates of a tool or of different tools of the same size being thus interchangeable.

When it is desired to replace a worn dressing wheel with a new wheel, the stop bar or latch 22 is raised as shown in Fig. 3 and the side plates thus released are pulled forward to the position shown in Fig. 3 and one, or both, if desired, is then removed from the shank head, the bearing pin slipping readily out from one or both of the anti-friction bearings. The worn wheel is then removed and a new one set in position, and the side plates are then returned to the position shown in Fig. 3 and then pushed inward on the shank head until the stop 22 snaps down into the notch 24. The tool is then ready for use.

It is to be understood that the invention is not to be limited to the exact construction shown and to which the foregoing description has been largely confined, but that it includes changes and modifications within the claims, and that features of the invention may be employed independently of other features thereof.

What is claimed is:

1. A dressing tool, comprising a shank, two removable side plates held against opposite sides of the shank with their ends extending beyond the end of the shank by a headed stud extending from the shank through a longitudinal slot in each side plate, a dressing wheel mounted between the extending ends of the side plates, and holding means for normally holding the side plates against longitudinal movement from their normal position on the shank, the side plates being movable longitudinally for re-

moval from the shank when released by said means.

2. A dressing tool, comprising a shank, two removable side plates held against opposite sides of the shank with their ends extending beyond the end of the shank by a headed stud extending from the shank through a longitudinal slot in each side plate, a dressing wheel mounted between the 10 extending ends of the side plates, the side plates being reversible endwise and the slots in the plates being located midway between the ends thereof and being enlarged at each end to permit removal of the plates when moved forward from their normal position on the shank, and means for normally holding the plates against longitudinal movement from their normal position on the shank.

20 3. A dressing tool, comprising a shank, two removable side plates held against opposite sides of the shank with their ends extending beyond the end of the shank by a headed stud extending from the shank through a longitudinal slot in each side plate, the side plates being reversible endwise and the slots in the plates being located midway between the ends thereof and being enlarged at each end to permit removal of the 30 plates when moved forward from their position on the shank and the plates having a recess in each end for receiving an anti-friction bearing, an anti-friction bearing removably set in the recess in the extending end of each plate, an axle pin, the ends of which are supported by the said anti-friction bearings, a dressing wheel mounted on said axle pin between the extending ends of the side plates, and means for normally holding the plates against longitudinal movement from their normal position on the shank.

4. A dressing tool, comprising a shank, two removable side plates secured to opposite sides of the shank with their ends extending beyond the end of the shank, means for holding the side plates against the sides of the shank formed to permit the plates to be removed when moved longitudinally from 45 their normal position, means for normally holding the side plates against longitudinal movement from their normal position on the shank, the side plates being reversible endwise and having a recess in each end for an anti-friction bearing, an anti-friction bearing removably set in the recess in the extending end of each plate, and a dressing wheel mounted between the extending ends of the side plates with the ends of its axle supported by said bearings.

5. A dressing tool, comprising a shank, two side plates removably secured to opposite sides of the shank with their ends extending beyond the end of the shank, an anti-friction bearing set in a recess in the

outer side of the extending end of each side plate, an axle pin mounted in said bearings having an enlarged central portion the ends of which form shoulders adapted to bear against the inner race of the bearings to prevent endwise displacement of the axle pin, a bushing free to rotate on the axle pin between the bearings, the bushing being of approximately the same length as the enlarged central portion of the axle pin and the ends of the bushing extending into the axle pin openings in the side plates, and a dressing wheel mounted free to rotate on said bushing.

6. A dressing tool, comprising a shank having at its head end parallel bearing faces on opposite sides thereof, two removable side plates set one against each of said bearing faces and extending beyond the end of the shank and held by a bolt extending through longitudinal slots in the side plates and having a fixed flat head on each end, means for holding the side plates in alignment, the slots in the side plates having enlarged inner ends to permit removal of the plates when moved forward from their normal position on the shank, means for normally holding the plates against longitudinal movement from their normal position on the shank, an anti-friction bearing set in the extending end of each side plate, an axle pin mounted in said bearings having an enlarged central portion the ends of which form shoulders adapted to bear against the inner race of the bearings to prevent endwise displacement of the axle pin, and a dressing wheel mounted on the axle pin between the extending ends of the side plates.

7. A dressing tool, comprising a shank having at its head end parallel bearing faces on opposite sides thereof and parallel shoulders at the longitudinal edges of said faces, two removable side plates set one against each of said bearing faces between said shoulders and extending beyond the end of the shank and held by a headed stud extending through a longitudinal slot in each side plate, the slots in the side plates having enlarged inner ends to permit removal of the plates when moved forward from their normal position on the shank, a spring latch for engaging notches in the edges of the side plates to hold the plates against longitudinal movement from their normal position on the shank, a dressing wheel mounted between the extending ends of the side plates, an axle pin on which said wheel is mounted free to turn, and removable bearings in said side plates for the ends of said axle pin.

8. A dressing tool, comprising a shank having at its head end parallel bearing faces on opposite sides thereof, two removable side plates set one against each of said bearing faces and extending beyond the end of the shank and held by a headed stud extending

through a longitudinal slot in each side plate, means for holding the side plates in alignment, means for normally holding the plates against longitudinal movement from their normal position on the shank, the side plates being reversible endwise and the slots in the plates being located midway between the ends thereof and being enlarged at each end to permit removal of the plates when moved forward from their normal position on the shank, and the plates, having a recess in each end for receiving an anti-friction bearing, an anti-friction bearing set in the recess in the extending end of each plate, an axle pin, the ends of which are supported by said anti-friction bearings, and a dressing wheel mounted between the extending ends of the plates on said axle pin.

9. A dressing tool, comprising a shank having at its head end parallel bearing faces on opposite sides thereof and parallel shoulders at the longitudinal edges of said faces, two removable side plates set one against each of said bearing faces between said shoulders and extending beyond the end

of the shank and held by a bolt set in a transverse slot in the shank extending through longitudinal slots in the side plates and having a fixed flat head on each end, a latch for holding the side plates against longitudinal movement in either direction from their normal position on the shank, the side plates being reversible endwise and the slots in the plates being located midway between the ends thereof and being enlarged at each end to permit removal of the plates when moved forward from their normal positions on the shank and the plates having an outside recess in each end for receiving an anti-friction bearing, an anti-friction bearing set in the recess in the extending end of each plate, an axle pin, the ends of which are supported by said bearings, a dressing wheel mounted between the extending ends of the side plates on said axle, and a detachable cover plate on the outer side of each side plate.

In testimony whereof I have hereunto set my hand.

JOHN SHEARMAN DONALDSON.
